UNITED STATES PATENT OFFICE.

CHARLES O. QUIMBY, OF WAKEFIELD, MASSACHUSETTS.

MOP.

1,304,094.

Specification of Letters Patent. Patented May 20, 1919.

Application filed February 19, 1914. Serial No. 819,616.

To all whom it may concern:

Be it known that I, CHARLES O. QUIMBY, a citizen of the United States, residing at Wakefield, in the county of Middlesex and 5 State of Massachusetts, have invented new and useful Improvements in Mops, of which the following is a specification.

My invention relates to mops and particularly to such as are used in polishing floors. 10 Mops of this character usually comprise a handle to which is fixed a head of wood or the like carrying a brush consisting of a bunch of yarn, and are used not only for wiping floors but also for washing windows, walls, and the like, to distribute polishing fluid over a floor, and to polish the latter. It is desirable that the head of the mop shall have no metal parts upon its exterior that would be liable to scratch or 15 mar furniture or woodwork or that may catch in draperies or textile furnishings of a room; that the brush can be easily and quickly attached to or removed from the head of the mop, and that the structure as a 20 whole shall be simple, strong and of light weight. The object of my invention is to improve the construction of mops of the character referred to and to provide a floor polishing mop which will meet all the requirements noted above.

To this end my invention consists of a mop comprising a handle at the lower end of which is provided a pair of opposed outwardly bowed arms, upon which arms the 25 body of the brush of the mop is removably mounted, the bowed shape of the opposed hooks serving to hold the brush from becoming accidentally detached while the mop is in use. This construction provides a light and 30 strong head which may be more or less flexible and does away with exterior fastening means likely to scratch or mar woodwork or furniture. Also it provides for ready removal of the brush when the latter needs 35 to be cleaned or another brush is to be substituted in its place on the mop head.

Other features of my invention are herein-after pointed out.

In the accompanying drawings:

50 Figure 1 is a side elevation of a mop constructed in accordance with my invention;

Fig. 2 is a plan view of the head of the mop shown in Fig. 1;

Fig. 3 is a plan view of the head of the 55 mop with the brush removed;

Fig. 4 is a section on the line 4-4 of Fig. 3;

Fig. 5 is a perspective view of one end of the brush hereinafter described; and

Fig. 6 is a detail illustrating the construction of the brush.

Fig. 7 shows a modification.

Having reference to the drawings, 1 represents the handle of my improved mop, 2 the head and 3 the brush. The handle 1 is herein shown as a length of pipe threaded at its lower end to receive upon it the interiorly threaded head 2. The head 2 is made with an interior chamber 4 which communicates with the interiors of two opposed outwardly bowed arms, 5, 5, which together form about three-quarters of a complete ring, leaving between their ends a gap of about ninety-degrees to permit the application or removal of the brush 3.

The brush 3 is made up of a number of strands of yarn 6 laid transversely between strips of fabric 7, (Fig. 6) that are fastened together and to the strands 6 by lines of stitching 8, the end of one of the strips 7 being carried around the end of the other and laid upon the latter before sewing. After the assembled parts of the brush have been fastened together by the stitches 8 the strips 7 are folded longitudinally as shown 85 in Fig. 5 and fastened in that position by lines of stitching 9 near their edges, thereby forming the strips into a flexible tube 10 and the loose yarn strands 6 are thus bunched at one side thereof. One end of the flexible 90 tubular body 10 is slid into position on one of the arms 5 and then the other end thereof is slid into position on the other arm 5. While the tubular body 10 is sufficiently flexible to permit of its being manipulated 95 or bent while sliding its ends onto or off of the arms 5, yet it is sufficiently stiff to insure its middle unsupported portion maintaining its position and shape while the mop is in use, and to cause the two bowed 100 arms 5 to hold the body 10 securely against accidental displacement without the use of any additional fastening devices.

It will be clear that when the arms 5, 5 are covered by the brush body 10 there are 105 no metal parts or fasteners of any kind upon the exterior of the head of the mop to mar or scratch woodwork or furniture or catch in draperies or hangings, when the mop is being used.

When used for washing windows and the like I may form screw threads 11 upon the upper end of the pipe-handle 1 so that a hose pipe 12 may be coupled thereto, and 5 provide a valve 13 in the handle-pipe 1 by means of which the flow of water to the head 2 may be controlled. The chamber 4 within head 2 communicates with the interiors of the hollow arms 5 which are provided along their under sides with outlets 14. When the valve 13 is opened water passes from the hose pipe 12 down through handle-pipe 1 into head 2, and from the latter into the arms 5 from which it discharges 15 through the outlets 14 into the body 10 of brush 3, thus thoroughly saturating the latter.

In the modification shown in Fig. 7 the upper end of the handle 1 has applied to it 20 a cap 15 formed with a central hole through which a stem 16 extends down through the pipe-handle. At its lower end the stem 16 carries a valve 17 which is held closed against the lower end of the pipe handle 1 by means of a spring 18 arranged between 25 the cap 15 and a collar 19 secured to the outer end of the stem. In this form of my invention the hollow handle 1 serves as a reservoir to hold a supply of floor polishing fluid or the like which may be supplied 30 to the brush 3 as required by the operator

pressing downward upon the outer end of the stem 16.

What I claim is:

1. A mop of the character described, 35 comprising a pipe-handle; a pair of hollow oppositely bowed arms near the lower end of said handle whose interiors communicate with the interior of the pipe-handle, said arms having outlet openings, and a brush 40 comprising a porous tubular flexible body having its ends removably and telescopically mounted on said arms.

2. In a mop, an absorbent mop head of 45 textile material having a porous, flexible and tubular body portion; a pair of hollow arms for supporting said mop head, each arm being made with outlets and having a free end in proximity to and permanently spaced from the free end of the other arm to permit 50 the ends of the tubular body portion of the mop head to be slipped upon said arms to be supported thereby, and a hollow handle with which said arms are connected, the interior of said handle communicating with 55 the interiors of said arms.

Signed by me at Boston, Massachusetts,
this 17th day of February, 1914.

CHARLES O. QUIMBY.
